Charles Grey. INVENTOR.

BY Richard B. Owen,
ATTORNEYS.

UNITED STATES PATENT OFFICE.

CHARLES GREY, OF CLINTON, IOWA.

WINDOW-ROD HOLDER.

Application filed April 6, 1927. Serial No. 181,541.

This invention relates to the class of curtains and shades and pertains particularly to a curtain rod and shade roller holder device.

5 The primary object of the present invention is to provide a curtain rod and shade roller holder of improved but simple design having a new and novel means for securing the device in position over a corner of a 10 window frame.

Another object of the invention is to provide, in a manner as hereinafter set forth, a curtain rod and shade roller holding device having positive window frame gripping 15 means capable of being operated without the use of any tool whatever and adapted to obtain a firm grip upon the window frame for maintaining a curtain rod and shade roller safely in position.

20 A further and final object of the invention is to provide a curtain rod and shade roller holding device of strong and durable construction, neat and attractive in appearance, and comparatively inexpensive to 25 manufacture.

Numerous other objects and advantages of the present invention will become apparent as the description of the same proceeds and the invention will be best understood from 30 a consideration of the following detailed description taken in connection with the accompanying drawing forming a part of this specification, with the understanding, however, that the invention is not confined to 35 any strict conformity with the showing of the drawing but may be changed or modified so long as such changes or modifications mark no material departure from the salient features of the invention as expressed 40 in the appended claims.

In the drawing:

Figure 1 shows the upper portion of a window frame in elevation, showing a pair of the devices embodying this invention, applied thereto.

Figure 2 is an end view of one of the fixtures embodying this invention.

Figure 3 is an inner side view of one of the fixtures.

50 Figure 4 is a vertical section taken substantially upon the line 4—4 of Figure 2.

Figure 5 is a transverse section taken upon the line 5—5 of Figure 3.

55 Referring now to the drawing in detail wherein like numerals of reference indicate corresponding parts throughout the several

views, the numeral 1 indicates generally the upper portion of a window frame the cross top rail being indicated by the numeral 2 and the side rails are indicated by the numerals 3.

The fixture embodying the present invention is shown in Figure 1 as applied, one to each corner of the window frame, and is indicated as a whole by the numeral 4.

This fixture comprises a front or escutcheon plate 5, having an inwardly extending flange 6 along one longitudinal edge and a top flange 7 projecting inwardly from the upper edge thereof. As shown in Figures 3 70 and 4, the top flange 7 is of greater length than the plate 5 but, this fixture is not confined to this construction, or the plate may be of a width equal to the length of the top flange.

The top flange 7 is provided with the central longitudinally extending slot 8 which extends from the point of joinder between this flange and the flange 6 to a point adjacent the free end of the flange as shown in Figure 4, and the side flange of the plate is provided with a similarly formed slot 9 which merges at one end with the slot 8 and extends throughout the major portion of the length of the flange 6 as shown in Figure 4.

85 Associated with the flanges 6 and 7 is a substantially L-shaped locking element indicated as a whole by the numeral 10, which is of substantially the same width throughout and comprises a normally horizontal arm 90 portion 11 having downstruck penetrating prongs 12 and the normally vertical portion 13. The element 10 is of substantially the same width throughout and is of slightly less width than the slots 8 and 9, the upper normally horizontal portion 11 being designed to fit in the slots 8 while the normally vertical portion 13 is designed to slidably fit in the slot 9.

100 Secured against the outer face of the flange 6 is a reinforcing plate 14, preferably formed of the same length as the flange 6 and having adjacent the upper end thereof, the short centrally positioned longitudinally extending slot 15.

105 Pivotedly secured to the plate 14 and the flange 6 by means of the rivet member 16 is a lever arm 17, the rivet 16 passing through the arm adjacent one end thereof. Pivotedly secured to the lever arm 17 inwardly of the pivot 16, by means of the rivet member 18 is one end of a link member 19, the other end

of the link extending beyond the pivoted end of the lever 17 and having a rivet 20 secured thereto and extending through the slots 15 for engagement with the portion 13 of the 5 locking element.

The inner face of the flange 6 is provided with one or more spurs 21 for engagement in the side edge of the window frame, and the inner edge of the plate 5 is provided with 10 the curtain shade roller bracket member 22 which extends at right angles from the face of the plate as clearly shown in Figures 1 and 2, while the face of the plate 5 is further provided with the outwardly and upwardly 15 extending arm 23 designed to receive the apertured end of a curtain rod, of the usual type.

In placing a fixture of the character described in position the lever arm 17 is swung 20 upwardly as indicated with red lines in Figure 2, and the plate placed in position against the front of the window frame with the flange 6 against the side edge of the frame and the flange 7 upon the top edge 25 thereof. The side flange 6 is then pressed inwardly to cause the spurs 21 to penetrate the frame after which the lever 17 is drawn downwardly bringing the locking element 10 down to cause the prongs 12 in the section 11 30 thereof to penetrate the top edge of the window frame. One edge of the lever 17 is provided with the instruck tongue 24 which, when the lever is swung to the position shown in Figure 2, engages in a recess 25 formed in 35 the flange 6, thus locking the arm 17 in down position.

From the foregoing it will be readily understood that a fixture of the character herein described may be easily and quickly applied to a window frame without tools and 40 without trouble and when in position is so securely held that curtain rods and shade rollers may be safely suspended therefrom without danger of becoming displaced. It 45 will also be seen that this bracket, while firmly gripping the window frame, will not in any manner mar the face thereof and will only cause light punctures in the surface of the edge of the frame.

50 Having thus described my invention, what I claim is:

1. A curtain rod and shade roller supporting fixture of the character described, comprising a plate member adapted to be 55 positioned against the face of a window frame, fixed means for engaging one edge of the frame, a shiftable frame engaging element designed to engage an adjacent edge of the frame, and pivoted lever operated 60 means for drawing said element to engaging position.

2. In a fixture of the character described, a plate element, flange members formed integral therewith for engagement over right 65 angularly related edges of the window

frame, means carried by one of said flanges for engaging said frame, a shiftable element extensible through the other of said flanges for engaging the frame edge therebeneath, and swinging means for drawing 70 said element to position.

3. In a fixture of the character described, a plate member adapted to be positioned against the face of window frame, at one corner thereof, inwardly extending flanges 75 carried by said plate one engageable over the top edge of the frame and the other engageable over the side edge thereof, a penetrating element projecting inwardly from one of said flanges, a reciprocable locking element carried by the fixture, and carrying frame edge penetrating elements extending substantially at right angles to the first mentioned penetrating element, and lever means for actuating said element to locking 80 position.

4. A fixture of the character described, comprising a plate member adapted to be positioned against the face of a window frame adjacent the corner thereof, a top and 90 a side flange carried by said plate engaging over corresponding top and side edges of the window frame, one of said flanges having a longitudinally extending slot formed therethrough, fixed means carried by one of said 95 flanges for engaging an edge of the window frame, a locking element including a flat body designed to position in said slot, means carried by the fixture for shifting the body into and out of position, and penetrating 100 elements carried by said body for penetrating the adjacent frame edge.

5. A fixture of the character described, comprising a plate member adapted to be positioned against the face of a window 105 frame adjacent the corner thereof, a top and a side flange carried by said plate engaging over corresponding top and side edges of the window frame, one of said flanges having a longitudinally extending slot formed therethrough, fixed means carried by one of said 110 flanges for engaging an edge of the window frame, a locking element including a flat body designed to position in said slot, penetrating elements carried by said body for penetrating the adjacent frame edge, and lever means secured to the outer side of the other flange for shifting said body to and from engaging position.

6. In a fixture of the character described, a plate member designed to be positioned against a window frame face adjacent one corner thereof, an inwardly projecting top and side flange carried by said plate for engagement over adjacent and corresponding edges of the window frame, each of said flanges having a longitudinally extending slot formed therein, and said slots merging at their inner ends, a locking element comprising a substantially L-shaped member 120 125 130

having the legs thereof adapted to position in the slots of said flanges to lie flush with the flanges, means engaging one of said legs for sliding the same longitudinally in its slot to lift the other leg from its slot in a parallel plane to its associated flange, a window frame edge penetrating element carried by said last mentioned locking element leg, and a frame edge penetrating element carried by that flange associated with the other leg of the element.

7. A curtain fixture of the character described, comprising a plate member designed to have curtain and shade roller supporting members carried thereby, and adapted to be positioned against a window frame at one corner thereof, an inwardly directed flange at the top and one side edge of said plate designed to overlie corresponding adjacent edges of the window frame, each flange having a centrally longitudinally extending slot formed therethrough, said slots merging at the point of jointure between the flanges,

a plate member overlying that flange formed at the side edge of the plate and having a relatively narrow longitudinally extending slot formed therethrough at the upper end thereof, a fixed locking element comprising a substantially L-shaped body having one leg positioned in the slot of the flange at the top edge of said plate, and the other leg positioned in the slot of the other flange, said last mentioned leg being designed to slide longitudinally of this slot, a lever member pivotally attached to said last mentioned leg, a link member having one end secured to said last mentioned leg and having its other end pivotally secured to said link inwardly of the pivotal point thereof, and window frame penetrating elements carried upon the first mentioned leg of said locking element, and upon that flange extending longitudinally of the plate.

In testimony whereof I affix my signature.

CHARLES GREY.
